UNITED STATES PATENT OFFICE.

SAMUEL CAME, OF PHILADELPHIA, PENNSYLVANIA, ASSIGNOR TO CROMPTON & KNOWLES LOOM WORKS, OF WORCESTER, MASSACHUSETTS, A CORPORATION OF MASSACHUSETTS.

LOCKING DEVICE FOR THE TAKE-UP MECHANISM OF LOOMS.

Application filed June 15, 1920. Serial No. 389,123.

To all whom it may concern:

Be it known that I, SAMUEL CAME, a citizen of the United States, residing at Philadelphia, in the county of Philadelphia and 5 State of Pennsylvania, have invented new and useful Improvements in Locking Devices for the Take-Up Mechanism of Looms, of which the following is a specification.

This invention relates to looms of the type 10 in which the take-up mechanism is actuated from a driving shaft through reversible gear connections. These connections commonly comprise a pair of reversely disposed bevel gears mounted on a sleeve which is splined 15 to a vertical driving shaft and is slidable thereon to bring either the upper or lower bevel gear into engagement with a double bevel gear which in turn meshes with a bevel pinion on a shaft of the take-up mechanism. 20 Under normal running conditions, the drive is through the upper bevel gear which is then in engagement with the double bevel gear.

It is the object of my invention to provide 25 a positive lock to hold the upper bevel gear in such engagement, so that the gears may not slip and separate during the operation of the loom. Such separation has been heretofore frequent, causing slipping of the teeth 30 past each other, with much wear and breakage thereof, and causing irregular operation of the loom which it is the purpose of my invention to avoid.

With this object in view, my invention as 35 shown herein embodies a locking device movable manually into position to engage and lock the mechanism by which the bevel gears are shifted, holding the same positively in a definite operative relation.

40 My invention further relates to arrangements and combinations of parts which will be hereinafter described and more particularly pointed out in the appended claims.

A preferred form of my invention is shown 45 in the drawings, in which

Fig. 1 is a side elevation of parts of a loom embodying my improved locking device, and

Figs. 2, 3 and 4 are detail views of separate parts of the locking device.

50 Referring to the drawings, I have indicated a portion of a loom frame 10 having supported thereon a driving shaft 11 carrying a bevel gear 12 meshing with a similar gear 13 loosely mounted on the lower end of

a vertical shaft 14 which is connected to 55 drive the head motion of the loom (not shown).

A clutch 15 is provided for connecting the gear 13 to shaft 14 and this clutch is controlled by a forked lever 16 mounted on a 60 fixed pivot 17 and connected by a link 18 to a bell crank 19 pivoted on the loom frame 10 and connected by a link 21 and pin 22 to a hand lever 23 pivoted at 24 on the loom frame. A weight 25 acts to hold the lever 65 and clutch in either operative or inoperative position.

A sleeve 35 is splined to the shaft 14 and is provided with upper and lower gears 36 and 37. As the sleeve 35 is moved on the 70 shaft 14, one or the other of the gears 36 and 37 will engage and drive a double bevel pinion 40 loosely mounted on a stud or bearing 41 on the loom side and meshing with a pinion 38 on the end of a shaft 39 which 75 constitutes the driving member for the take-up mechanism of the loom (not shown).

An annular groove 42 is formed in the upper end of the sleeve 35 and the sleeve is 80 vertically positioned by a forked lever 43 pivoted at 44 on the loom frame. A link 46 is connected to the outer end 45 of the lever 43 and at its upper end the link 46 is connected to a bell crank 47 pivoted at 48 on the loom frame and connected by a link 49 85 to the lower end of a reverse lever 50, pivoted at 51 on the loom frame and having a handle 52.

All of the parts thus far described are or 90 may be of the usual construction and form no part of my invention, which relates specifically to a device or attachment for positively locking one of the bevel gears in driving engagement with the double bevel gear 40.

95 For this purpose I provide a bracket 26 adjustably mounted on the loom frame 10 and secured in position thereon by a bolt or bolts 27. The bracket 26 has an arm or projection 28 in which a stud 29 is secured, forming a bearing for a latch or locking lever 30. The lever 30 has a transverse slot or opening 31 at the end of one of its arms and is pivotally connected at 32 to a link 33, the upper end of which is pivoted at 34 to 100 the bell crank 19 previously described.

105 The link 33 is preferably arranged for adjustment by providing a separate head 33a

threaded on the lower end thereof. With this arrangement, the position of the locking lever 30 relative to the clutch lever 16 may be accurately adjusted.

Having described the construction of my improved device, the operation thereof will be readily apparent. Assuming that the weighted end 25 of the lever 23 has been swung to the right to stop the rotation of the shaft 14, the handle 52 of the lever 50 may then be pushed in or to the left, raising the end 45 of the lever 43 and depressing the forked inner end thereof. This causes the sleeve 35 to slide downward on the shaft 14 so that the gear 36 will engage with the double bevel gear 40. With the parts in this position, the hand lever 23 may be swung back to the position shown in Fig. 1, causing the clutch 15 to engage the gear 13 and drive the shaft 14 and at the same time advancing the locking lever or latch 30 so that an offset portion of the lever 43 will be seated and firmly held in the slot 31.

With the parts in this position, the lever 23 is securely locked and upward movement of the bevel gear 36 is effectually prevented.

If it is thereafter desired to reverse the drive of the take-up mechanism, the hand lever 23 is first moved from the position shown in Fig. 1 to release the lever 43 and disconnect the clutch 15, after which the lever 50 may be used to reverse the engagement of the bevel gears 36 and 37.

Whilst I have described and shown the best known means at the present time for

effecting the object in view, I wish it clearly understood that I do not limit myself to the precise pattern and arrangement of parts disclosed, but reserve the right to make such other changes and modifications that may reasonably be construed as falling within the scope and ambit of the appended claims.

Having described my invention, what I claim as new and desire to secure by Letters Patent, is:

1. The combination with the reverse lever of a loom take-up mechanism and the driving connection therefor including a clutch, of a locking device comprising a bearing, a bell crank pivoted on said bearing and having a forked arm cooperating with said reverse lever, and a connection from the other arm of the bell crank to a manually operated device also controlling said clutch through which the take-up mechanism is driven.

2. In a loom having a take-up mechanism, in combination, a driving mechanism therefor including reversely disposed sliding bevel gears, a hand lever to shift said gears to reverse the driving engagement thereof, operating connections between said hand lever and said gears, and a device engaging said connections between said lever and said gears and effective to positively lock said connections from movement and to thereby positively prevent disengagement of said gears when in a definite operative relation.

In testimony whereof I affix my signature,
SAMUEL CAME.
